DESIGN FOR A LUBRICATOR SIGHT FEED

Bengt E. Folke, Mamaroneck, N. Y., assignor to
Nathan Manufacturing Company, New York,
N. Y., a corporation of New York

Application April 3, 1940, Serial No. 91,443

Term of patent 14 years

To all whom it may concern:

Be it known that I, Bengt E. Folke, a citizen of the United States and a resident of the village of Mamaroneck, in Westchester County and State of New York, have invented a new, original, and ornamental Design for Lubricator Sight Feeds, of which the following is a specification, reference being had to the accompanying drawing, forming a part thereof.

In the drawing,

Fig. 1 is a plan view of a lubricator sight feed embodying my new design;

Fig. 2 is a front elevational view of the same; and

Fig. 3 is a side elevational view of the same.

I claim:

The ornamental design for a lubricator sight feed, substantially as shown.

BENGT E. FOLKE.
